DESIGN FOR A GAME APPARATUS

Leon M. Gibbs, Birmingham, Ala.

Application January 18, 1935, Serial No. 54,909

Term of patent 14 years

To all whom it may concern:

Be it known that I, Leon M. Gibbs, a citizen of the United States, residing at Birmingham, in the county of Jefferson and State of Alabama, have invented a new, original, and ornamental Design for a Game Apparatus, of which the following is a specification, reference being had to the accompanying drawing, forming a part thereof.

In the drawing,
Fig. 1 is a perspective view of a game apparatus, showing my new design; and
Fig. 2 is a plan view of the same.

I claim:

The ornamental design for a game apparatus, substantially as shown.

LEON M. GIBBS.
